FOOT OPERATED AIR COMPRESSOR

Thomas E. Crockett, Corpus Christi, Tex.

Application May 5, 1947, Serial No. 746,109

2 Claims. (Cl. 230—172)

1

My invention relates to air compressors adapted for use in inflating automobile tires and for other purposes.

An important object of the invention is to provide a compressor or pump so constructed that it is manually operated by the foot or feet, in a convenient manner so that the major portion of the weight of the operator may be applied in such operation.

A further object of the invention is to provide a compressor or pump which is extremely simple in construction, and is supported substantially vertically in use, without liability of the same falling or tipping over.

A further object of the invention is to provide a tire pump having a pumping cylinder equipped with inlet and outlet valves near one end thereof so that the air may readily enter the cylinder upon the up stroke of the plunger.

A further object of the invention is to provide a pump of the above mentioned character having an improved plunger construction for effecting a proper gas tight engagement between the plunger and pumping cylinder.

A further object of the invention is to provide a pump of the above mentioned character having long telescoping tubes or cylinders, one of which carries the foot pedal or pedals and plunger and associated elements, whereby twisting action is eliminated and a positive guide is provided during operation.

A further object of the invention is to provide a pump of the above mentioned character having a large base and pedal or pedals secured to the reciprocating cylinder or tube near its bottom so that there is no tendency for the pump to tilt or fall over.

A further object of the invention is to provide a pump of the above mentioned character which is neat and attractive in appearance.

Other objects and advantages of the invention will be apparent during the course of the following description.

In the accompanying drawings forming a part of this application and in which like numerals are employed to designate like parts throughout the same:

Figure 1 is a perspective view of a compressor or pump embodying my invention.

Figure 2 is a central vertical longitudinal section through the pump.

Figure 3 is a plan view of the same.

Figure 4 is a horizontal section taken on line 4—4 of Figure 2.

Figure 5 is a bottom plan view of the pedal unit.

2

In the drawings, wherein for the purpose of illustration is shown a preferred embodiment of my invention, the numeral 10 designates a large circular horizontal base, preferably provided with a marginal annular flange or foot 11. Arranged above the base 10, and concentric therewith, is a cylindrical boss 12, cast integral therewith. The base 10 and integral parts, are preferably an aluminum casting. The base 10 is provided at its top and within the boss 12 with a sump recess 13.

Formed integral with the boss 12 and base 10 is a radial inlet valve housing 14, having a main bore 15, the outer end 16 of which is threaded and leads to the atmosphere. A plug 17 is held within the outer end 16 and has screw threaded engagement therewith, and this plug affords a valve seat 18 and has an air inlet opening 19. Mounted within the bore 15 is a check ball valve 20, to engage the seat 18, and held against displacement by a transverse pin 21. The bore 15 leads into an inner bore 22, leading into the sump chamber 13. Disposed diametrically opposite the air inlet valve is an air outlet valve, including a radial valve casing 23, integral with the boss 12 and base 10. This valve casing has a main bore 24, provided at its inner end with a valve seat 25, to be engaged by a check ball valve 26, held against displacement by a transverse pin 27. The bore 24 leads into an inner bore 28, discharging into the sump chamber 13. The main bore 24 has an outer threaded portion 29 for receiving the screw threaded portion 30 of a coupling 31, carrying a reduced portion 32, extending into a flexible hose 33, clamped thereon as shown at 34. This hose is provided at its free end with a suitable fitting for connection with the valve of a pneumatic tire or the like.

The numeral 35 designates a lower stationary vertical tube or cylinder, preferably formed of steel, and the lower end of this cylinder is held within the tubular boss 12, and is preferably screwed into the same and has a gas tight joint therewith. The cylinder 35 engages the end or bottom 36 and the lower end of this cylinder is in free communication with the sump chamber 13.

Mounted to slide upon the lower tube or cylinder 35 is an upper reciprocating vertical tube or cylinder 37, preferably formed of steel. The upper cylinder has a free sliding fit upon the lower cylinder 35 and remains in permanent telescoping relation therewith.

Arranged within the cylinder 37 is a plunger 38, which is vertical and carries a plunger at its lower end, which operates within the lower

cylinder 35. The plunger rod 38 is provided at its lower end with a reduced screw threaded extension 39, forming a shoulder 40, and a rigid steel washer 41 is carried by the reduced extension 39 and engages against the shoulder 40. A packing cup 42, preferably formed of leather is carried by the reduced extension 39 and is arranged between the washer 41 and a companion rigid steel washer 43. Disposed beneath the washer 43 is a resilient washer 44, preferably formed of artificial rubber of the type which resists the action of oil. The screw threaded portion 39 carries a nut 45, having a pilot extension 46, to center the resilient washer 44 and clamp the washer 43 against the packing cup 42. The resilient washer 44 is held within the skirt of the packing cup and spreads it radially so that it is brought into proper contact with the inner face of the cylinder 35. It is thus seen that a plunger assembly is carried by the lower end of the plunger rod 38, for operation within the cylinder 35. The upward movement of this plunger assembly is limited by an inwardly projecting annular bead or shoulder 47 formed in the cylinder 35. The bead 47 is arranged well below the top end of tube or cylinder 35 and nearer the longitudinal center of the cylinder than its top end.

This bead or shoulder forms a stop or support for a rigid steel washer 48, arranged above it, and a compressible coil spring 49 engages against this washer and surrounds the plunger rod 38. At its upper end, the plunger rod is rigidly secured to a cap 50. This connection is preferably effected by forming an apertured depression 51 in the cap 50, and this apertured depression receives a reduced extension 52, of the plunger rod, the upper end of this reduced extension being spread or peened to provide a head 53. The cap 50 is rigidly mounted upon the top of the casing 37 by any suitable means, such as welding.

Rigidly mounted upon the lower end of the upper cylinder 37 is a horizontal pedal unit 54, including oppositely arranged radial pedals 55, having their upper surfaces roughened, as shown. These pedals 55 are formed integral with an annular hub 56, and longitudinal reenforcing ribs 57, are preferably provided. The hub is internally threaded as shown at 58 for receiving the lower screw threaded end of the upper cylinder 37. It is thus seen that the pedal unit is arranged at the bottom of the upper cylinder, and this provides the pump with a low center of gravity when force is applied to the pedal, reducing the tendency for the pump to tip over. When the upper cylinder 37 is in the lowermost position the plunger assembly will project outwardly beyond the cylinder 35, with the base removed, providing excess to the plunger assembly. During the normal operation of the pump, the plunger assembly of course reciprocates within the lower cylinder.

The operation of the pump is as follows:

The flexible hose 33 is connected with a pneumatic tire, or the like. The spring 49 maintains the upper cylinder 37 in the uppermost position while the pump is not being used. A foot or feet are placed upon the pedal unit 54, and the upper cylinder is reciprocated vertically upon the lower relatively stationary cylinder 35. The plunger including the packing cup 42 reciprocates vertically within the lower cylinder. Upon each upward or suction stroke of the plunger within the cylinder 35, the ball valves 20 and

26 move radially inwardly due to the vacuum formed in the cylinder 35. The outlet check valve 26 is closed or seated against the seat 25, and the inlet check valve simultaneously opens 5 to admit air through the inlet opening 19, bore 15, bore 22, and sump recess 13 into the lower cylinder 35. When the next down or pumping stroke of the plunger occurs, the air in the cylinder 35 is compressed, and the ball check valves 20 and 26 move radially outwardly. The inlet check valve 20 becomes seated and closed, while the outlet or exhaust check valve 26 is opened. The compressed air therefore passes through the sump recess 13, of bore 23, bore 24, and through the hose 33 to the pneumatic tire, or the like.

The pump is designed for ease of operation in the pumping up of automobile tires. When it is used to pump up a large tire requiring relatively high air pressure, such as a heavy truck tire, more than one person may assist in the pumping operation. For example, one person can place a foot upon each pedal 55, and a third person can place a foot upon the cap 50, and all three can pump in unison.

25 It is to be understood that the form of my invention herewith shown and described is to be taken as a preferred embodiment of the same, and that various changes in the shape, size, and arrangement of parts may be resorted to, without departing from the spirit of my invention or the scope of the subjoined claims.

Having thus described my invention, what I claim is:

1. A foot operated pump for pneumatic tires or the like, comprising a relatively wide base including an upstanding portion having a substantially vertical recess and air inlet and outlet ports in communication with the recess, check valves for the inlet and outlet ports, a lower upstanding tube having its lower end secured within the recess, said tube having a substantially horizontal bead formed therein and extending entirely about the inner surface of the tube, said bead being at an elevation well below the upper end of the tube and nearer the longitudinal center of the tube than the upper end thereof, a substantially flat washer arranged within the upper portion of the tube and having its marginal edge mounted upon the bead and having a central opening, an upper reciprocatory tube mounted upon the lower tube and provided at its top end with a cap, a rod secured to the cap and extending within the tubes and passing through the opening in the washer and extending below the bead, a plunger mounted within the lower tube beneath the bead and upon the lower end of the rod, the bead serving to contact the plunger when the plunger is moved upwardly to limit such upward movement, a compression spring surrounding the rod and engaging between the cap and washer, and a foot operated member having an intermediate portion provided with an opening for receiving the lower end of the upper tube which is held within such opening, said foot operated member including oppositely arranged pedals carried by said intermediate portion.

2. A foot operated pump for pneumatic tires and the like, comprising a relatively wide base including an upstanding portion having a substantially vertical screw threaded recess and air inlet and outlet ports in communication with such recess, check valves for the inlet and outlet ports, a lower upstanding tube having its lower end screw threaded and engaging within

the screw threaded recess, said tube having a substantially horizontal annular bead formed from the material of the tube and projecting radially inwardly and extending entirely about the inner surface of the tube, said annular bead being at an elevation well below the upper end of the tube and nearer the longitudinal center of the tube than the upper end thereof, a substantially flat washer arranged within the upper portion of the tube and having its marginal edge supported by the annular bead and being provided with a central opening, an upper reciprocating tube mounted upon the lower tube and in telescopic relation therewith and provided at its top end with a cap and having its lower end screw threaded, a rod secured to the cap and extending within the tubes and passing through the opening in the washer and extending below the annular bead, a plunger mounted within the lower tube beneath the bead and upon the lower end of the rod, the bead serving to contact the plunger when the plunger is moved upwardly to limit its upward movement, a compression spring surrounding the rod and arranged between the

cap and washer, and a foot operated member having an intermediate sleeve portion provided with a screw threaded opening for receiving the lower screw threaded end of the upper tube, said foot operated member including diametrically oppositely arranged foot pedals carried by the intermediate sleeve portion.

THOMAS E. CROCKETT.
